UNITED STATES PATENT OFFICE

IRWIN W. DAVID, OF NEW YORK, N. Y.

FOOTWEAR

Application filed July 19, 1930. Serial No. 469,045.

This invention relates to an improvement in footwear, and in particular to the construction of the type of shoe ordinarily, though not necessarily, worn by women.

5 Among the objects of this invention are to provide a shoe which will have a forepart that is flexible and expansible with the foot, giving greatly increased comfort, and which has a heel of greater strength and rigidity than the forepart in order to provide a sturdy and rigid heel construction substantially free from lateral expansibility, to provide a shoe which with existing machinery may be built in combination widths, as for example, a heel 10 of A width and forepart of B width, to provide in combination with a soft and flexible forepart a heel portion capable of containing a counter to give strength to the heel and enable it to be formed in the so-called tailored shape, to provide a shoe which will not tear the stocking in the heel portion, to provide a shoe which is flexible and yielding in the forepart but at the same time is capable of containing a metal shank concealed in the 15 shank portion to strengthen it and support the foot, and to provide a shoe having a molded and expansible forepart which may be combined with a full-breasted heel.

In the drawings annexed hereto, and which 20 form a part of this specification,

Fig. 1 is a vertical elevation of a shoe built in accordance with my invention, and having a Cuban heel.

Fig. 2 is a vertical section on the line 2, 25 2 of Fig. 1.

Fig. 3 is a vertical section on the line 3, 3 of Fig. 1.

Fig. 3a is a vertical section on the line 3, 3 of Fig. 1, showing the method of insertion of 40 the stitches before the leather flanges 12 are restored to their normal position.

Fig. 4 is a plan view of a sole piece cut to a suitable shape for incorporation in a shoe embodying my invention, and showing in dotted lines the approximate outline of the shoe when the edges have been molded up.

Fig. 5 is a vertical section through a portion 45 50 of the shoe of Fig. 1 taken in the plane indicated by the line 5, 5 of Fig. 3.

Fig. 6 is a vertical section similar to that of Fig. 5, except that the shoe disclosed embodies a full-breasted heel instead of a Cuban heel.

Fig. 7 is a vertical section along the central 55 lengthwise axis of my shoe, indicated by the line 7, 7 of Fig. 2 and Fig. 3.

Fig. 8 is a vertical section on the line 8, 8 of Fig. 7.

Like reference numerals in the several 60 drawings indicate like parts.

In accordance with my invention I form a sole 1 having a heel portion 2 (see Fig. 4) of the usual size and shape and having a forepart 3 materially larger than the shape 65 of the shoe which it is desired to form. There is thus provided a marginal edge 4 extending around the forepart of the sole. This marginal edge is molded upwardly 70 while the leather is moist, to the position shown in section in Fig. 2, thus initially giving shape to the forepart of the shoe from the toe to the instep. To the upstanding marginal edge, thus formed, there is attached a suitable upper 19. For convenience, I disclose herein an upper composed of woven 75 leather strands 5 and 6 but it will be understood that the invention is not limited in scope to any particular form of upper. The woven leather strands engage with the upstanding margin 4 through a series of holes 7, 7 punched therein. The upper for the forepart of the shoe is attached to the upturned marginal edge 4 of the sole 1 from the toe of the shoe rearwardly along each side of 80 the forepart to the point 8.

Rearwardly of the point 8 no further laterally-extending flange is provided on the sole 1, but the sole is narrowed to the normal width at the point 8, and rearwardly thereof 85 has a cross-section which is approximately rectangular at any point. Throughout the instep and heel portions rearwardly of the point 8, the sole may be attached to the heel upper portion as follows: the marginal edges 90 of the sole are partially split longitudinally thereof and a channel formed as indicated at 9, 9 in Fig. 3a with depending flanges 12, 12. The quarter 10 is then affixed to the sole 95 1 as indicated in Fig. 3a and the inturned 100

flanges 20 of the quarter 10 and the channel 9 are fastened together by stitches 11. After the stitches 11 are in place, the depending flanges 12, 12 are returned to the position shown in Fig. 3 and glued or pasted in position to cover the exposed stitching. A sock lining 13 may be inserted within the shoe to cover the exposed stitches on the inside of the shoe and to provide a smooth and attractive-appearing inner surface.

10 It will be understood that the channeling 9 is carried forward from the rear of the shoe to a point only as far forward as the quarter 10 extends. Ordinarily this will be in the neighborhood of point 8 (see Fig. 1).

15 A modified form of shoe is disclosed in Fig. 6. In this shoe the sole rearwardly extending from the point 8 is laterally split across its full width and a lower lip or tongue 14, 20 suitably scived, is curved downwardly and attached by glue or paste to the forward face of the heel lift 15. The upper portion of the sole is carried backwardly to the extreme rear of the shoe and the inturned flange 20 of 25 the quarter 10 is attached to it by suitable stitches 11 as indicated in Fig. 6. It is thus possible to employ a full-breasted heel in combination with an expandable and flexible forepart in my shoe.

30 A still further modification is indicated in Fig. 7 wherein the sole is carried upwardly and backwardly from the point 8 to a point of abutment at 16 with the forward face of the heel lift 15 but does not extend to the 35 rear of the shoe. In this form of shoe the inturned flange 20 of the quarter 10 is nailed directly to the heel or lift by suitable nails 17, the sock lining 13 is affixed in place in the usual manner, and the strengthening 40 shank referred to below is firmly attached to the sole piece and the heel so as to unite the shoe in a strong unitary structure.

45 The arrangement here disclosed, wherein the quarter is stitched to the margin of the sole for a portion of the instep of the shoe, permits the employment in the instep, and between the sole 1 and the sock lining 13, of a metal strip or shank 18 which serves to strengthen the shoe at the instep and prevent downward breakage of the leather at 50 this point while the shoe is in use. This shank is inserted in direct contact with the sole 1 and, after being glued in place, is covered by the sock lining 13 which serves to conceal it. It is thus possible in my shoe to 55 provide an arch strengthening element and a stiff heel structure without sacrificing softness and flexibility in the forepart where the shoe is most apt to become uncomfortable in use.

60 It is also possible, within the scope of my invention to attach the inturned flanges 20 of the quarter 10 to the sole 1 or to the heel lift 15 in any other manner, as for example 65 by stitching entirely through the sole with-

out preliminary channeling in a manner which will be understood, or by nailing, or by gluing or other attachment by adhesive.

I claim:

1. A shoe comprising a sole member whose forepart is upwardly molded at the marginal edges of the shoe so that the outer surface of the lower portion of the side of the shoe in its forepart is continuous and integral with the under surface of the sole in said forepart, perforations near the upper edge of said upwardly molded portion for the attachment of an upper, said sole in the part of the shoe rearwardly thereof having an approximately rectangular cross section 75 without upturned marginal edges, and a quarter having inturned flanges at the base thereof for attachment to that portion of the sole which is approximately rectangular in cross-section.

2. A shoe comprising a sole member whose forepart is upwardly molded at the marginal edges of the shoe so that the outer surface of the lower portion of the side of the shoe in its forepart is continuous and integral with the under surface of the sole in said forepart, perforations near the upper edge of said upwardly molded portion for the attachment of an upper, said sole in the part of the shoe rearwardly thereof being 80 laterally split whereby it is divided into a lower portion for attachment against the forward face of the heel and an upper portion having an approximately rectangular cross-section without upturned marginal edges, and a quarter having inturned flanges at the base thereof for attachment to that portion of the sole which is approximately rectangular in cross-section.

3. A shoe comprising a sole member whose forepart is vertically upturned at the marginal edges of the shoe so that the outer surface of the side of the shoe in its forepart is continuous and integral with the under surface of the sole in said forepart, the upstanding edges of the sole terminating in the region of the shank, said sole member rearwardly of said point having its marginal edges terminating approximately in the plane of the sides of the shoe without being upturned, a shank piece of strengthening material attached to said sole member in the shank region thereof, and a quarter having inturned flanges at the base thereof for attachment to said sole member.

4. A shoe comprising a sole member whose forepart is upwardly molded at the marginal edges of the shoe to an elevation above the plane of the sole sufficient to give marked lateral expansibility when the shoe is in use and so that the outer surface of the lower portion of the side of the shoe in its forepart is continuous and integral with the under surface of the sole in said forepart, perforations near the upper edge of said upwardly molded

portion for the attachment of an upper, said sole in the part of the shoe rearwardly thereof having an approximately rectangular cross section without upturned marginal edges, and a quarter having inturned flanges at the base thereof for attachment to that portion of the sole which is approximately rectangular in cross-section.

5
10 In testimony whereof, I have signed my name to this specification.

IRWIN W. DAVID.
